Inventor:
John F. McCanna

UNITED STATES PATENT OFFICE.

JOHN F. McCANNA, OF DEVINE, TEXAS.

GUN-BARREL CLEANER.

Application filed November 4, 1920. Serial No. 421,658.

To all whom it may concern:

Be it known that I, JOHN F. McCANNA, a citizen of the United States, residing at Devine, in the county of Medina and State 5 of Texas, have invented certain new and useful Improvements in Gun-Barrel Cleaners, of which the following is a specification.

This invention relates to devices for cleaning the barrels of shot guns, rifles and the 10 like.

The primary object of my invention is to provide a simple and novel means for cleaning and also oiling the barrel of a gun in a most satisfactory manner.

15 Heretofore, devices employed for this purpose have been unsatisfactory by reason of the fact that when used by an inexperienced person the surface of the barrel will invariably be injured. It is the purpose of 20 the present invention to provide a cleaning device which will not injure the barrel, especially the muzzle end of a shot gun, the symmetry of which controls the pattern of the shot.

25 This object is attained by the provision of a handle-stop on the cleaner rod which when properly set, limits the projection of the cleaner pads through the barrel. That is, the pads are not passed entirely through 30 the barrel but sufficiently to insure thorough cleaning and prevent irregular wear of the muzzle end.

I have also aimed to provide a gun barrel cleaner in which the cleaning elements, 35 pieces of fine wire gauze, may be quickly and easily applied or removed as occasion may require.

A further object is to provide a cleaner having a pair of resilient wire-gauze covered 40 fingers adjustable very simply to accommodate gun barrels of different gauges.

My invention also contemplates the construction of a gun barrel cleaner embodying the foregoing objects, in such simple and 45 novel design as to be thoroughly practical and efficient for the purposes in mind and to be capable of economical production.

Other objects and attendant advantages 50 will be appreciated by those familiar with this art as the invention becomes better understood by reference to the following description when considered in connection with the accompanying drawings, in which—

55 Figure 1 is a view of a gun barrel cleaner embodying my invention, as used in cleaning a shot gun;

Fig. 2, a view of the gun cleaner removed from the gun;

Figs. 3 and 4, enlarged sectional views 30 through the cleaning pad and handle ends, respectively, of the gun cleaner;

Fig. 5, a top view of the pad holder shown in Fig. 3;

Fig. 6, a cross-sectional view taken on the 65 line 6—6 of Fig. 4;

Fig. 7, a view of a piece of wire gauze to be wrapped about one of the cleaner pad fingers; and

Fig. 8, a view of a modified form of pad 70 holder arms.

My improvements consist, generally stated, of a rod 11 equipped at one end with a cleaner pad holder designated generally by character 12 and at the opposite end with 75 a combined handle and stop 13. The rod may be made up of two or more sections detachably connected together, in the present instance these rods being tubular and connected by threaded coupling studs 14. 80

The pad holder is in the form of a pair of curved resilient fingers 15 mounted in any suitable manner on the rod 11 and adapted to be spread or closed by adjustment of a block 16 interposed between the 85 fingers. In the example shown in Fig. 3, the fingers are formed integral with a tubular shank 17 which is freely rotatable on a threaded pin 18 fixed to the rod 11. The block 16 screwed onto the pin 18 acts as a 90 wedge when drawn between the inclined faces of the fingers 12 by turning the rod relatively to the fingers and spreads the arms or causes them to contract, depending on whether the wedge is tightened or 95 loosened, as will be obvious. These fingers might be formed from a single piece of sheet metal as shown in Fig. 8, the shank of the arms abutting against the shoulder on the rod and a wedge block 19 being employed 100 to spread the fingers 21. The wedge blocks 16 and 19 function alike to cause spreading or contracting of the fingers 15. To spread the fingers they will be held by one hand and the rod 11 turned to the right 105 with the other hand, thereby turning the screw 18 and causing the block 16 or 19 as the case may be, to move axially on the screw 18 to the right, viewing Figs. 3 and 8, spreading the fingers 15 outwardly. By 110

turning the rod 11 in the opposite direction the fingers 15 will be contracted due to their spring tendency to return to a closed position. The fingers in either form are preferably provided along their longitudinal edges with small spurs 22 which serve to retain the cleaning pads in position. The cleaning pads are preferably small rectangular sheets of fine wire gauze 23, one adapted to be wound about each finger 15 so as to entirely envelop the same and conform to the shape thereof. These pads may manifestly be easily applied and removed whenever necessary.

15 The handle 13 is so constructed as to be freely slideable lengthwise on the rod 11 and provision is made for securing the handle at any position to which it has been moved. To this end, any suitable clamping device 20 such for example as a set screw, may be employed. At present I have equipped the handle with a transverse bushing 24, through which the rod 11 passes. A set screw 25 in the bushing 24 is adapted to be 25 tightened at will to hold the handle at any set position.

From the foregoing it will be manifest that before cleaning a gun the handle stop should be set. That is, the cleaner rod will 30 be passed through the barrel from the breech end thereof, as shown in Fig. 1, until the elongated fingers are about half way projected beyond the muzzle end of the barrel, whereupon the handle should be 35 set against the breech end to serve as a stop. This insures against passing the cleaner pads entirely through the barrel and causing uneven wear on the muzzle end by the fingers spreading and being forced together again over the edge of the barrel. In time, such uneven wear would destroy 40 the symmetry of the pattern, but by the use of my improved cleaner the barrel will be cleaned evenly from end to end and without liability of injuring the pattern of 45 the shot.

Another feature is the ready adaptability of the cleaner to different gauge guns. This is automatically accomplished to a certain 50 extent by the resiliency of the fingers, and to a fine degree of nicety by adjustment of the block 16 to obtain the most suitable tension. It will also be noted that by reason of the finger construction the wire gauze 55 will be securely held in position and yet may be quickly removed and replaced by new gauze at any time.

Still another feature is the presentation 60 of new cleaning surfaces to the internal wall of the barrel while the cleaner is in the barrel. That is, by turning the handle 13 to increase the tension on the fingers 15, the arc of the fingers will be changed, causing the line of contact to approach the rear 65 end of the fingers in proportion to the in-

creased pressure. It follows that by contracting and expanding the fingers by such adjustment, new cleaning surfaces will be presented to the barrel during the cleaning operation, thereby enabling better and more effective cleaning.

By dropping a little oil on the gauze pads they serve the purpose both of cleaning and oiling. The gauze body retains the oil which works out by capillary attraction. 75 Thus the oil is, in fact, self-feeding.

It is believed that the foregoing conveys a clear understanding of the principles and objects prefaced above, and while I have illustrated but a preferred embodiment, it shall be understood that various changes might be made in the construction without departing from the spirit and scope of the invention as expressed in the appended claims.

I claim:

1. A gun barrel cleaner comprising, a rod, a pair of resilient fingers mounted on one end of the rod with capacity to turn about the axis of the rod and arched outwardly at their medial portions providing converging forward and rear ends, removable cleaning means on said fingers, and means operated by rotation of the rod with respect to said fingers for exerting outward pressure on the fingers and for varying said pressure, whereby to vary the local presentation of the cleaning means to the internal wall of the barrel at points longitudinally spaced on said fingers.

2. A gun barrel cleaner comprising a rod, a pair of resilient fingers carried by the rod and curved outwardly at their medial portions, providing converging forward and rear ends, barrel cleaning means on said fingers, and means operative between the rod and fingers for adjusting said fingers in the barrel by rotation of the rod with respect to the fingers to vary the local presentation of the cleaning means to the internal wall 110 of the barrel at points longitudinally spaced on said fingers.

3. A gun barrel cleaner comprising a rod, cleaning pads carried on one end of the rod, means whereby said pads may be expanded by rotation of the rod with respect to the pads, and a handle adjustable lengthwise on the opposite end of the rod constituting a stop for limiting projection of the cleaner pads through a barrel, and constituting also a manually operable means for moving the cleaner lengthwise in the barrel and a manually operable means for rotatably adjusting the rod to expand or contract the cleaner pads.

4. A gun barrel cleaner comprising a rod, a cleaning device carried on one end of the rod, means whereby said device may be expanded and contracted by rotation of the rod with respect to said device, and a com-

bined handle and stop adjustable lengthwise on the opposite end of the rod and adapted for limiting projection of said device through a barrel and for rotation to adjust 5 said cleaning device.

5. A gun barrel cleaner comprising a rod having a fixed threaded member at one end, a member having a shank rotatably supported on said end and carrying a pair of 10 separated cleaning fingers, and a part threadingly engaged on said threaded member between the fingers and adapted by relative rotation of the finger member and rod to effect greater or less separation of the 15 fingers, whereby such adjustment of the fingers may be effected by rotation of the opposite end of the rod when the fingers are disposed in a barrel.
6. A gun barrel cleaner including cleaner- 20 supporting parts in the form of elongated oppositely curved, resilient fingers, said fingers having inwardly pointed serrations along their longitudinal side edges, and cleaning means wrapped about said fingers 25 and held against displacement by said serrated edges.
7. A gun barrel cleaner, comprising a suitable rod equipped at one end with a pair of resilient fingers arched outwardly at their

medial portions so as to provide converging 30 forward and rear ends, the former of which are separated and freely resilient, inwardly directed spurs along the longitudinal edges of the fingers, and a wire gauze sheath wrapped about each finger and retained in 35 position by said spurs.

8. The combination of a rod having a reduced threaded end, a member fitting loosely on said end and having a pair of resilient curved fingers, a member threadingly engaged on said end between the fingers and adapted by relatively turning the first mentioned member and the threaded member to effect expansion or contraction of said fingers, and cleaning material carried by each 40 45 finger and effective on the outer curved sides thereof.

9. A gun barrel cleaner comprising a rod, a threaded member fixed on one end of the rod, a plurality of resilient, arched fingers 50 supported on said rod with capacity to turn about the axis thereof, and a wedge block threadingly engaged on said threaded member and located between said fingers whereby to separate the latter by rotation of the rod 55 with respect to the fingers.

JOHN F. McCANNA.
